D 16559

UNITED STATES PATENT OFFICE.

CHARLES CASPER, OF MERIDEN, CONNECTICUT, ASSIGNOR TO THE MERIDEN SILVER PLATE COMPANY.

DESIGN FOR A CLOCK-CASE.

SPECIFICATION forming part of Design No. 16,559, dated March 9, 1886.

Application filed December 3, 1885. Serial No. 184,649. Term of patent 7 years.

To all whom it may concern:

Be it known that I, CHARLES CASPER, a citizen of the United States, residing at Meriden, in the county of New Haven and State of Connecticut, have invented and produced a new and original Design for a Clock-Case, of which the following is a specification, reference being had therein to the accompanying drawing, which represents a clock-case made in conformity with my novel design, said case being in the form of a bottle having a neck, A, stopple B, and flattened body C. Around the body C is the representation of a bead, G, partly cut away at the bottom of the body C to form a flattened surface. On the flattened body C is a dial, D, surrounded by a beading, E, and at one side of the upper part of the case is the representation of a handle, F. The representation of the stopple B is here-
in shown as being ornamented by radial stripes b and band b'.

I claim—

1. The design for a clock-case herein shown, consisting of the representation of a bottle with neck A, stopple B, handle F, and flattened body C, having dial D, surrounded by beading E, and the said body being surrounded by beading G, partly cut away at the bottom. 25
2. The design for a clock-case herein shown, consisting of the representation of a bottle with a neck, A, stopple B, having radial stripes b and band b', handle F, flattened body C, having dial D, surrounded by beading E, and the said body being surrounded by beading G, partly cut away at the bottom. 30

In testimony whereof I affix my signature in presence of two witnesses.

CHARLES CASPER.

Witnesses:

ROBERT H. CURTIS,
E. T. HOPKINS.
